Inventor,
Charles W. Leguillon
By G. R. C.
Atty

UNITED STATES PATENT OFFICE.

CHARLES W. LEGUILLOON, OF AKRON, OHIO.

LOOP.

Application filed July 7, 1923. Serial No. 650,092.

To all whom it may concern:

Be it known that I, CHARLES W. LEGUILLOON, a citizen of the United States, and a resident of Akron, county of Summit, State of Ohio, have invented certain new and useful Improvements in Loops, of which the following is a specification.

This invention relates to metal attachments or loops such as used, for example, in attaching the holding straps to swinging doors and known in the trade as "footman loops," but while the invention will be described for this special purpose, it is obvious that it is of broader application and may be placed to other uses and in other relationships.

The object of the invention is to improve upon the design of these loops or brackets, particularly with a view to strengthening them and making them easier of application than the old form of loop. For this purpose the device has been redesigned and modified to the form shown, although it will be apparent that exact conformance to details of construction are not essential to the carrying forward of the invention, and it may be modified within the scope thereof and within the scope of the claims.

In the drawings:

Figure 1 is a view showing the location of the improved device on a swinging door of an automobile;

Figure 2 is a view of the device removed;

Figure 3 is a side view partly in section; and

Figure 4 is a section on the line 4-4 of Figure 2.

The improved device or loop comprises a plate indicated generally by the numeral 10 which is provided with two parallel extensions or arms 11 connected by a central bar 12, thus making a plate of general U-shape form, in each portion of which is located an aperture 13 to receive a fastening screw 14. On the body of the plate and parallel to one another are upstanding lugs 15 which are elevated above the body of the plate as shown and are formed on their inner or facing surfaces with recesses

50 or grooves 16 which extend from the under surface of the plate and terminate within the lugs so that when the plate is attached to the surface 17 the grooves are closed.

The grooves or slots are preferably per-

pendicular to the plate, although this is optional, and extend to points on the lugs above the surface of the plate. A pin or bar 18 is arranged to be received in the grooves so that when the plate is removed from its surface the pin may be placed in position and when the plate is secured by the screws the pin will be retained within the grooves and confined thereby.

The construction shown and described has many obvious advantages over the ordinary form of loop, one being apparent from the drawings, in which the strap 19, to hold the swinging door, is shown received over the pin by the loop or eye in the end of the strap. By the design of the loop shown, it is an easy matter to insert the eye of the strap over the pin and then to insert the pin within the grooves of the plate before the plate is secured in position. The location of the screws serves to secure the plate in position without danger of loosening.

The device may have other uses than that shown, and the invention is not necessarily confined to the exact location as shown, nor to exact conformance with the details of construction. It will be seen that a simple, but strong and easily applied loop has been provided.

What is claimed is:

1. As a new article of manufacture, a loop comprising a plate having parallel arms, lugs perpendicular to the plate, parallel grooves formed within the opposing faces of the lugs, said grooves being open from the bottom of the plate, and a loose pin received within and confined by the grooves, the plate having means by which it may be secured in position.

2. As a new article of manufacture, a loop comprising a plate having a central portion and parallel arms, lugs formed on the plate and rising from the body thereof, the plate having grooves placed in opposed relationship opening from the underside of the plate and terminating within the lugs, and a pin loosely received within and confined by the grooves.

3. A footman loop comprising a plate of substantial U-shape and having grooves within the opposed faces of the parallel arms, the grooves opening from the bottom of the plate and terminating within the

arms, a pin receivable within the grooves and confined thereby, and a strap having an eye received over the pin.

4. A footman loop comprising a plate having a central portion and parallel arms and having grooves within the opposed faces of the said arms, the grooves opening from the bottom of the plate and terminating within the arms, a pin receivable within the grooves, securing means for the plate located in the arms and in the central portion of the plate, and a strap having an eye received over the pin.

5. As a new article of manufacture, a loop comprising a plate having grooves opening from the under side of the plate and ter-

minating within the body of the plate, and a pin receivable within the grooves and confined therein by the plate.

6. As a new article of manufacture, a loop comprising a plate, spaced parallel arms on said plate having grooves opening from the base of the plate, and a pin receivable within the grooves and confined thereby.

7. As a new article of manufacture, a loop comprising an attaching plate, the under surface of which is recessed, and a pin receivable within the recess and confined therein upon attachment of the plate in position.

CHARLES W. LEGUILLOON.
